UNITED STATES PATENT OFFICE.

EDWARD EVERETT COTHRAN, OF WRIGHT, CALIFORNIA.

AIRPLANE PROPELLER.

Application filed May 11, 1925. Serial No. 29,493.

The invention relates to a propeller for lifting, sustaining, moving and landing an airplane or other vehicle in the air, and the objects of the invention are, first, to enable airplanes to ascend vertically from the earth, the water or a ship; second, to enable airplanes to descend vertically from the air; third, to enable airplanes to land safely from flight in the air upon earth, water or deck of a ship; fourth, to increase the carrying and sustaining capacity of airplanes; fifth, to better the stability and safety of airplanes; and, sixth, to increase the power, speed and efficiency of airplanes in connection and combination with a tractor type of propeller.

I attain these objects by the mechanism illustrated in the accompanying drawing, in which

20 Figure 1 is a diagrammatic view of part of the invention shown with the understructure of the airplane;

Figs. 2, 3 and 4 are detail views of the propeller blades; and Fig. 5 a side view of a 25 monoplane in accordance with my invention.

Referring to Fig. 1, the understructure (1) of the airplane is pierced by the vertical shaft (2) and above such understructure is the crankshaft (3) of an engine, the latter not shown.

Affixed rigidly to the shaft (2) half of the propeller blades, fully disclosed in Figs. 2, 3, and 4, are shown.

The crankshaft (3) and the propeller shaft 35 (2) are of one piece of metal.

While the vertical shaft indicates that a horizontal engine is employed preferably to a vertical engine, still, the latter may by appropriate gearing be used.

40 The blades shown in Fig. 1, are affixed to the propeller shaft (2) as illustrated in Figs. 2, 3, and 4 with a squared cross-section of the shaft (2).

As the blades are all rigidly attached to 45 the shaft (2) either by welding, bolts and lock-nuts or by some other suitable means, the vertical shaft is better made square after leaving its lowest bearing or journal-box in the understructure.

50 The four blades shown in Fig. 2 must be affixed to the shaft (2) immediately below the understructure (1) Fig. 1, leaving only clearance space. These blades are of maximum length from tip to tip.

55 The four blades shown in Fig. 3 must be

affixed to the said shaft next below the four blades of Fig. 2, leaving a small clearance, and are shorter from tip to tip.

The four blades shown in Fig. 4 must be affixed to the propeller shaft next below the 60 four blades of Fig. 3, leaving a small clearance and are shortest from tip to tip.

In each of the three sets of blades, two blades are set at right angles to two blades, making a total of twelve propeller blades. 65 All the blades are designed to move toward the right with the shaft to which they are rigidly attached.

The direction of the motion of the blades may, of course, be reversed with the engine 70 and shaft.

The propeller blades should be constructed of metal or wood, preferably of thin steel which combines tensile strength and elasticity. 75

Referring in this connection to Figs. 2, 3, and 4, the edges of the respective blades, particularly at the spines (5, 5, 5, 5,) should be thicker and stronger than the remaining parts of the blades which should be made as thin, light and elastic as is consistent with the necessary strength.

Elasticity in the blades is important as it permits many small flexures that aid in the effective compression of the open air by the 80 blades with the consequent increase of power.

The shoulders of the blades of Fig. 2 are very closely affixed to the propeller shaft.

The shoulders of the blades of Figs. 3 and 4 are joined to the shaft by stout bolts (4) 90 and lock-nuts or are joined by welding steel rods to the shaft and said shoulders, leaving in either case an opening of a few inches of space between the shaft and said shoulders for the purpose of allowing an unobstructed suction of air upward past these two sets of blades.

The purpose of these arrangements is to allow the free ingress of air around the shaft and to cause the blades of Fig. 2 to strike a 100 large volume of compressed air around the shaft.

As the vertical shaft and the three sets of blades of different lengths and curved surfaces are whirled around, the air is forced in 105 circles and spirals along the blades under a high compression, tending to produce a vacuum, (see Fig. 1) within the propeller.

However, this tendency to produce a 110 vacuum is not realized, as a powerful suc-

tion from the air below is created within the area of the propeller, especially next the shaft.

This suction is naturally along the line of least resistance upward, thereby inducing great lifting force as the air rushes in to be impacted, compressed and thrust by all the blades.

The general outline of the entire propeller somewhat resembles the shape of a tornado, water-spout or whirlwind, and the mechanism operates qualitatively upon similar principles, namely; meeting of winds blowing in opposite directions, compression of air, production of partial temporary vacuums, and vortices of upward and translatory motion.

As a heavy object may be lifted more easily upon an inclined plane and as one of the primary purposes is to cause an airplane to rise directly upward, the blades are not only multiplied beyond the ordinary number employed in aerial propellers, but the inclined planes, circular or screw-like in form, are very pronounced, particularly in Fig. 3.

25 The blades in Fig. 2, largely compress and thrust the air downward and outward from the shaft (2), as a center to the tips as a circumference, forming a vortex of gyrating air within and around the propeller.

30 The blades in Fig. 3, compress and thrust the air more outward and less downward in a circle than the blades in Fig. 2.

The blades in Fig. 4, being of minimum length from tip to tip, and freely admitting air around the shaft, compress and thrust the air more largely outward in a circle.

35 The combined effects of the two sets of blades, shown in Figs. 3 and 4, are, first, to increase the tendency of the propeller to form a vacuum next the vertical shaft, and, second, to oppose and prevent the vacuum being formed by simultaneously creating a powerful upward suction of air against the lower surfaces of the blades of Fig. 2, especially around the shaft.

40 This suction, in turn, concentrates air under high compression, beneath the blades of Fig. 2.

The final result is a propeller of great 45 lifting and sustaining power.

The application of the engine's power through the propeller below the understructure of the airplane lowers the center of gravity of the whole machine and contributes much to its stability.

45 The blades shown in Fig. 4, while shaped like those of Fig. 2, are reversed in the order in which they are affixed to the shaft and in which they strike the air.

50 In other words, the four blades of Fig. 4, may be deemed upside down to the four blades of Fig. 2.

55 As the shaft whirls all the blades in the same direction, this arrangement causes the air to be displaced and thrust in a different

manner and angles by these two sets of blades; and as the blades of Fig. 3, are unlike in shape to those of Figs. 2 and 4, all the three sets have different functions in the propeller.

70 The vertical propeller may be made to move the airplane horizontally by manipulation of the rudder, although it is the particular intention of petitioner to employ two engines in the airplane: one to drive the 75 described propeller from a vertical shaft, another to drive a tractor propeller from a horizontal shaft.

75 Referring to Fig. 5, (6) shows a tractor propeller of four blades shaped precisely 80 like the blades of Fig. 2, (7) is a monoplane body, (8) is a monoplane wing, (9) shows the vertical rudder, (10) the horizontal rudder, (11) the landing-gear, and, (2) the vertical propeller shaft with the blades affixed 85 to it.

80 The vertical propeller shaft and its described blades do not extend so far below the understructure of the airplane as to require any particular modification of the 90 present landing-gear except that more space is allotted between the front and rearward gears.

85 A small clearance between the upper blades (Fig. 2) and the understructure (1) 95 Fig. 1, allows of an exceedingly compact construction of the entire propeller.

90 The clearance spaces or rather distances between the blades of Fig. 2 and Fig. 3, and between the latter and Fig. 4 may, for instance, be not more than one inch.

95 Having described and illustrated my invention, I claim:

1. An airplane propeller consisting of a 100 vertical metal shaft, directly connected with the vertical crank-shaft of the airplane engine, extending vertically downward through and beneath the understructure of the airplane, four compound-curved propeller blades preferably of steel rigidly 105 affixed at the shoulders of the blades to the shaft at right angles to each other and immediately beneath said understructure with only clearance space for the blades when whirled with the shaft, four shorter propeller blades of similar material, each blade more acutely curved, rigidly affixed to the shaft at right angles to each other immediately beneath and without contact with the 110 first-mentioned four blades, four compound-curved and still shorter blades of similar material of the same shape as those first-mentioned but set upside down rigidly 115 affixed to the shaft by bolts and lock-nuts with the shoulders of the blades slightly separated from the shaft immediately beneath the second-named four blades and without contact with the latter.

120 2. An airplane propeller of the character 125 described and shown in combination with

a monoplane and monoplane propeller, consisting of a vertical metal shaft extending vertically downward through and beneath the understructure of the monoplane, said shaft directly connected as one piece of metal with the crank-shaft of the monoplane's engine, four compound-curved propeller blades, preferably of steel, rigidly affixed at the shoulders of the blades to the vertical shaft at right angles to each other and immediately beneath said understructure with only clearance space for the blades when whirled around with the said shaft, four shorter propeller blades of similar material, each blade more acutely curved, rigidly affixed to the shaft at right angles to each other, immediately beneath and without contact with the first-mentioned four blades; four compound-curved and still shorter propeller blades of similar material and of the same shape as those first-mentioned but affixed to the shaft upside down by bolts and lock-nuts with the shoulders of the blades slightly separated from the shaft and immediately beneath the second-described four blades and without contact with the latter; a tractor propeller with four compound-curved propeller blades affixed to the end of a horizontal shaft at the front of the monoplane, driven by a second engine and adapted to operate simultaneously in conjunction with the first-described propeller of the monoplane.

EDWARD EVERETT COTHRAN.
